UNITED STATES PATENT OFFICE.

JAMES HENRY MASON, OF LONDON, ENGLAND.

ADDING-MACHINE.

1,194,205.

Specification of Letters Patent.

Patented Aug. 8, 1916.

Application filed October 23, 1915. Serial No. 57,446.

To all whom it may concern:

Be it known that I, JAMES HENRY MASON, citizen of the United States of America, residing at 34 Great St. Helens, in the city of London, England, have invented certain new and useful Improvements in or Relating to Adding-Machines, of which the following is a specification.

This invention relates to adding machines or devices and has more particular reference to the kind in which two toothed counting rings are rotatably and concentrically mounted in a casing, one of the said rings being adapted to be rotated by a pencil or stylus engaging with the teeth on the ring, while the other ring is automatically moved or rotated to the extent of one tooth for every complete revolution of the counting ring which is rotated by the pencil.

20 The chief object of the present invention is to provide a portable machine of the above kind of a convenient size and shape to enable it to be placed quite close to the figures to be added, so that the user can glance at the figures and the machine practically at the same time, so as to avoid continually moving the eyes first from the figures and then to the adding machine as is usual with adding machines hitherto proposed.

30 According to this invention the counting rings are maintained concentrically in the same plane by means of a member or casing which is in the form of a ring or annular frame thereby imparting a ring-like formation to the device or machine. By making the adding device of ring-like formation it is possible to place the device on the book or a paper bearing the figures to be added so that the figures are positioned within the 40 space circumscribed by the device, and are thus conveniently situated so that the observation of the figures and the operation of the device can be effected practically simultaneously with ease. The said ring-like or 45 annular member or casing comprises upper and lower portions between which the counting members are held concentrically in the same plane, the said portions being suitably secured together for example by an annular 50 flange or wall disposed between the concentric counting rings. The upper portion of the said ring-like member or casing is provided with an opening at its outer periphery to expose several peripheral teeth on the 55 outer counting ring so that the teeth can be

engaged by a pencil to rotate the counting ring; a radial aperture (or apertures) is provided close to the said peripheral opening in the casing through which aperture the sum or total of the added numbers can be observed.

The counting rings are provided with projections or other equivalent devices by means of which the rings can be readily set to zero or to any desired number and for 65 the purpose of facilitating this operation the front or upper portion of the ring-like casing is suitably numbered. Improved means are also provided for enabling the inner counting ring to be rotated to the extent of one tooth for every complete revolution of the outer counting member. Means may be provided for guiding the pencil or stylus into engagement with the exposed teeth on the outer counting ring to enable 70 the device to be operated quickly and accurately. The keyboard may also be especially arranged to facilitate the operation of the device.

In order that the said invention may be 80 clearly understood and readily carried into effect, I will proceed to describe the same more fully with reference to the accompanying drawings, in which—

Figure 1 is a front view of one form of 85 the improved device. Fig. 2 is a similar view to Fig. 1 showing the upper part of the casing removed. Figs. 3 and 4 are fragmentary cross sectional views of the machine taken on the lines 3—3 and 4—4 of Fig. 90 2 respectively showing in two different positions the automatic means for moving the second counting ring. Fig. 5 is similar to Fig. 2 but illustrates a fragmentary view of a modification. Fig. 6 is a fragmentary 95 front view showing the aforesaid guiding means and the modified keyboard and Fig. 7 is a fragmentary sectional perspective view taken on the line x—x of Fig. 6.

In the example shown the counting rings 100 1 and 8 are concentrically and rotatably mounted in the annular casing 2 which comprises upper and lower portions 2 and 2^a, the said counting rings being separated by a narrow annular wall or flange 5 which 105 also serves to connect the upper and lower portions of the casing together. The upper portion 2 has a peripheral opening 3 to expose teeth 6 or the like on the outer periphery of the counting ring 1 and radial 110

apertures 4 and 10 are provided in the casing, through which apertures consecutive numbers 00—01—02, etc., to 99 on the counting rings can be successively exposed by rotating the said rings. Teeth or projections 9 are provided on the outer periphery of the inner counting ring 8; there are one hundred teeth on each counting ring and the consecutive numbers on each ring are situated 10 in close proximity to the teeth on each ring. The peripheral opening 3 on the casing is large enough to expose several (say nine or twelve) of the teeth 6 on the ring 1 and the face of the casing adjacent to the said 15 opening 3 may be marked with the numbers 1 to 9 (or more if desired) so as to constitute the key-board of the device.

The counting ring 1 indicates units and tens up to 99 and the counting ring 8 indicates hundreds and thousands so that the maximum total which can be obtained by the said rings is 9999.

When it is desired to add several numbers or units a pencil or stylus is placed in 25 the peripheral opening 3 against the tooth on the counting ring adjacent to the number on the keyboard which corresponds to the unit to be added; the ring 1 is then rotated or moved by the pencil until the latter 30 comes in contact with the end 7 of the said peripheral opening 3 or any other suitable stop; as a result of this rotary movement the number which was visible in the totalizing aperture 4 prior to the rotary movement 35 of the counting ring is increased by the number which has been added. For example, if 00 is seen in the aperture 4 and the unit 9 is the first of the figures to be added, the pencil is placed against the tooth 40 corresponding to the number 9 on the keyboard and is then moved until stopped as aforesaid. Thus the counting ring is rotated to the extent of 9 teeth and the number 09 is then visible through the totalizing aperture 4 in the cover 2. If the next figure 45 or unit to be added is 3 the pencil is placed in the peripheral opening 3 against the tooth adjacent to the number 3 on the keyboard and the pencil is again moved as before until stopped by the end 7 of the peripheral opening 3 so that the counting ring is further rotated to the extent of three teeth to show the sum or total 12 through the aperture 4 in the casing. In this way 50 numbers up to a total of 99 can be rapidly added.

In order to automatically rotate the counting ring 8 to the extent of one tooth when required an appropriate actuating device 60 may be provided which at the requisite time engages with the teeth on the counting ring 8 and moves it to the required extent so that the movement of the counting ring 1 from 99 to 00 can be accompanied by a movement 65 of the counting ring 8 to indicate the pres-

ence of one hundred or a change in the hundreds if the sum total which is visible through the totalizing aperture exceeds one hundred. The actuating device shown in Fig. 3 comprises a ball 11 located in a recess 12 in the counting ring 1 and adapted to move with the latter. The said ball 11 is guided in similarly shaped annular grooves 13 in the upper and lower portions of the casing 2, which grooves are so arranged that the ball will be kept outside the partition 5 during the greater part of revolution of the counting ring 1. A gap 14 is formed in the partition 5 and the grooves 13 are so arranged at this point 70 75 80 that the ball is guided at the desired time into engagement with one of the teeth 9 on the counting ring 8 thus causing the latter to be moved to the extent of one tooth when the counting ring 1 is moved.

The arrangement shown in Fig. 5 can also be used for automatically moving the counting ring 8; in this example the said annular flange or partition 5 between the two counting rings 1 and 8 may normally 90 retain a spring pawl 15 out of engagement with the second ring 8, but it may be formed with a gap 16 to allow the pawl 15 to engage with and move the ring 8 to the extent of one tooth at the requisite time.

One of the teeth 15* situated adjacent to the numbers 99—00 on the counting ring 1 is longer than the other teeth 6 and projects outwardly to enable the counting ring to be quickly set to zero or to any other desired number. For this purpose the outer face of the cover is provided with consecutive numbers from 00—01, etc., to 99 and by setting the tooth 15* close to any one of these numbers the corresponding number on the counting ring 1 will be visible through the aperture 4.

The counting ring 8 is provided on its internal periphery with a tooth or projection 16 by means of which the ring may be readily rotated until the numbers 00 or any desired number thereon appears in the aperture 10. The projection or elongated tooth 15* on the counting ring 1 also enables the ring 1 to be quickly set to show in the aperture 4 any desired number or figure which is to be carried over from the units column to the tens column and so on. For instance if the total of the units column is 562, the unit 2 of the total is noted on a book or paper and in order to carry over 56 to the next or tens column, the ring 1 is then rotated by the tooth 15* until the latter comes opposite to the number 56 on the cover. The number 56 on the counting ring 1 will then show in 110 115 120 125 the aperture 4 and the addition of the tens column of figures can be then effected and in this way the carried over number 56 is included.

In the modification shown in Figs. 6 and 130

7 the upper portion of the casing 2 is formed with approximately radial grooves 17 which are numbered to form the keyboard. The pencil can be placed in any one of the 5 grooves and moved along the groove into engagement with the tooth 6 on the counting ring 1 adjacent to the groove in which the pencil was placed. The radial grooves present a larger area for the reception of the 10 pencil when adding thereby facilitating the selection of the numbers on the keyboard and at the same time insuring accuracy. A curved groove 18 is provided near the periphery of the lower portion 2^a of the casing under the exposed teeth on the counting ring 1 to constitute a guide for the pencil when effecting the rotary movement of the counting ring and also to prevent the pencil from slipping out of engagement with the 15 tooth. The keyboard may be divided into two parts, one being marked with the odd numbers and the other with the even numbers (see Fig. 6) and stops 19 and 20 may be provided for the odd and even numbers respectively, for the purpose of limiting the movement of the pencil when effecting the rotation of the counting ring 1. Thus when a pencil is placed opposite numeral 8 on the keyboard, or in fact on any of the even numbers thereof, the pencil may move the ring 1 until it comes into contact with stop 20, while if placed opposite numeral 9 or any 20 uneven number thereof, it may move the ring 1 until it comes into contact with the stop 19. The ultimate result in either case is therefore the same as in the single keyboard type, although the double key board provides for more ready and quick operation in the hands of unskilled persons.

40 The counting rings being narrow can be concentrically arranged in a small annular space and the casing does not appreciably increase the combined width of the two rings so that the adding device may be made to 45 take the form of a neat and convenient ring of only a few inches in diameter, which can be easily carried in the pocket or arranged on a book or sheet containing the figures to be added. The parts may be made in celluloid vulcanite or thin light metal. Of 50 course more than two counting members or rings may be provided if desired but two is

found to be a convenient number for general use.

What I claim and desire to secure by Letters Patent of the United States is:—

1. An adding device comprising in combination a casing, a counting ring provided with teeth engageable by a stylus to rotate the ring, the said casing being provided with 60 a key board having upper radially disposed and numbered guiding grooves for the stylus.

2. An adding device comprising a casing composed of upper and lower portions, a 65 counting ring rotatably held between said portions, means on said counting ring which may be engaged by a pencil to rotate the said ring, the upper casing portion being cut away partly along its peripheral edge to 70 form a keyboard and expose the said pencil engaging means, and the lower casing portion having a groove along and below said board and said pencil engaging means to prevent the pencil from accidental displacement from the said engaging means.

3. An adding device comprising a casing composed of upper and lower portions, a counting ring rotatably held between said portions, means on said counting ring which 80 may be engaged by a pencil to rotate the said ring, the upper casing portion having a numbered keyboard exposing the said pencil engaging means and provided with a pair of spaced pencil stops, and the numbers 85 of the keyboard being arranged in two separate series, one series in advance of each of said pencil stops, for the purpose described.

4. An adding device comprising in combination a casing; a counting ring rotatably supported in said casing and adapted to be rotated by a pencil, a keyboard on said casing which is divided into two parts to separate the odd and even numbers thereof and 95 a stop for each part of the keyboard to limit the movement of the pencil.

In testimony whereof, I affix my signature in the presence of two witnesses.

JAMES HENRY MASON.
